UNITED STATES PATENT OFFICE

CONRAD FERDINAND ÅLLER, OF STOCKHOLM, SWEDEN, ASSIGNOR TO THE DE LAVAL SEPARATOR COMPANY, OF NEW YORK, N. Y., A CORPORATION OF NEW JERSEY

CENTRIFUGAL SEPARATOR BEARING

Application filed August 30, 1928, Serial No. 302,952, and in Sweden November 3, 1927.

In centrifugal separator bowls difficulty is experienced in effectively preventing the entrance of moisture into the bowl spindle bearing, which is usually mounted with some elasticity in the separator frame. One of the main objects of this invention is to so support and enclose the spindle bearing as to make it possible to provide means for effectively excluding moisture therefrom. The invention comprises a bearing support and means associated therewith to prevent penetration of moisture to the spindle bearing. The invention also comprises certain preferred structural features which have been found to provide a satisfactory and efficient spindle bearing as well as to effectuate, in a high degree, the object of preventing moisture penetration.

The drawing, which illustrates such an embodiment of the invention, is a vertical sectional view of the bearing, the part of the spindle adjacent thereto, the bearing housing and supporting means and the moisture excluding means.

The bowl spindle *a* turns within a bearing *b*, which is preferably, but not necessarily, a ball bearing, as shown. The inner ring of the bearing is confined, top and bottom, between a shoulder *d* on the spindle and a spring plate *e* carried by the spindle. The outer ring of the bearing is confined, top and bottom, between a shoulder *g* on a bearing housing *f* and an elastic ring *h* held in a groove in said housing.

Surrounding housing *f* is a fixed frame *i*. An elastic device, such as a spring *k*, is placed between frame *i* and housing *f*, the face of the latter being dished in to afford a seat for the spring.

From the top of housing *f* extends outward a hood *m* the downwardly extending skirt of which surrounds and is spaced from the upper end of frame *i*. From the top of housing *f* extends inward a member having a neck *n* which surrounds and is spaced from the spindle. Secured to the spindle is a collar *o* which has a skirt that surrounds and is spaced from neck *n*.

In the described construction the non-rotating bearing housing *f* participates in the

vibrations and oscillations of spindle *a* and bearing *b*, making it possible to provide a very narrow clearance between the neck *n* and the spindle and between the neck *n* and the skirt of collar *o*. The bearing is thus very effectively protected against the entrance of moisture from the bowl housing.

In order that the bearing housing and the hood carried thereby shall not touch the frame when the bowl is vibrating, there should be a large play between the housing and the frame. The enclosure of the upper part of the frame *i* by the hood *m* tends to prevent the admission of moisture inside of the frame; but if moisture should penetrate thereinto, it would not be harmful, since the housing *f* prevents the moisture from contact with the bearing enclosed thereby.

What I claim and desire to protect by Letters Patent is:

1. A bearing for a separator bowl spindle comprising, in combination with the bowl spindle, a spindle bearing, a surrounding frame, a bearing housing, an elastic support for the bearing housing between the same and the frame, a hood extending outward from the bearing housing over and down around and spaced from the frame, and means to exclude penetration of moisture into the space over the bearing between the bearing housing and the spindle.

2. A bearing for a separator bowl spindle comprising, in combination with the bowl spindle, a spindle bearing, a surrounding frame, a bearing housing, an elastic support for the bearing housing between the same and the frame, a hood extending outward from the bearing housing over and down around and spaced from the frame, a member extending inward from the bearing housing having an upwardly extending neck surrounding the spindle, and a collar carried by the spindle above said neck and having a depending skirt surrounding said neck.

3. A bearing for a separating bowl spindle comprising, in combination with the spindle, a bearing housing, a ball bearing the outer ring of which is seated in said housing and the inner ring of which is fixed on the spindle, a frame surrounding said housing, an out-

wardly extending hood carried by the housing and extending over and surrounding the upper part of the frame, an inwardly extending member having a neck surrounding the 5 spindle, and a collar on the spindle having a skirt surrounding said neck.

4. A bearing for a separator bowl comprising, in combination with the bowl spindle, a surrounding housing in which the bearing is 10 seated, a frame, an elastic support between the frame and the housing, and means for excluding moisture from the bearing; said means comprising a hood on the housing which surrounds the upper part of the frame and be- 15 tween which and the frame is a relatively wide clearance, a member which is carried by the spindle, and a second member which is carried by the housing and surrounds the spindle and is surrounded by the first mem- 20 ber and with which it has a relatively narrow clearance.

In testimony of which invention, I have hereunto set my hand, at Stockholm, Sweden, on this 15th day of August, 1928.
